UNITED STATES PATENT OFFICE

152,132

DESIGN FOR AN ALARM CABINET

Richard E. Young, Detroit, Mich.

Application May 9, 1947, Serial No. 138,937

Term of patent 7 years

(Cl. D72—1)

To all whom it may concern:

Be it known that I, Richard E. Young, a citizen of the United States, residing at Detroit, in the county of Wayne and State of Michigan, have invented a new, original, and ornamental Design for an Alarm Cabinet, of which the following is a specification; reference being had to the accompanying drawings, forming a part hereof.

Figure 1 is a face view of an alarm cabinet, showing my new design.

Figure 2 is a top plan view of the same.

Figure 3 is a rear elevational view of the same.

Figure 4 is an end view of the same.

I claim:

The ornamental design for an alarm cabinet, as shown.

RICHARD E. YOUNG.
